UNITED STATES PATENT OFFICE.

STEPHEN O. STANFIELD, OF ORANGE, CALIFORNIA.

ROTARY VALVE.

1,093,891.

Specification of Letters Patent.

Patented Apr. 21, 1914.

Application filed August 29, 1912. Serial No. 717,722.

To all whom it may concern:

Be it known that I, STEPHEN O. STANFIELD, a citizen of the United States, residing at Orange, in the county of Orange and 5 State of California, have invented certain new and useful Improvements in Rotary Valves; and I do hereby declare the following to be a full, clear, and exact description of the invention, such as will enable others 10 skilled in the art to which it appertains to make and use the same.

This invention relates to rotary valves for internal combustion engines; and it consists in the novel construction and combination 15 of the parts hereinafter fully described and claimed whereby the admission and exhaust of a plurality of power cylinders are effected and controlled by a single valve.

In the drawings, Figure 1 is a front view 20 of an internal combustion engine constructed according to this invention, and showing portions of its casing in section. Fig. 2 is a front view of the rotary valve, showing the valve casing in section, and drawn to a 25 larger scale. Fig. 3 is a cross-section through the valve and its casing, taken on the line *x*—*x* in Fig. 2. Fig. 4 is a cross-section through the valve, taken on the line 30 *y*—*y* in Fig. 2. Fig. 5 is a longitudinal section through a portion of the valve, taken on the line *z*—*z* in Fig. 4. Fig. 6 is a section on line *w*—*w* in Fig. 2.

The engine illustrated is provided with 35 four power cylinders arranged side by side, but more or less than four power cylinders may be used in carrying out this invention, four cylinders being a satisfactory number, and being described in order to clearly set forth the invention. These four power cylinders are all similar to each other, and each cylinder has a piston 2, and a connecting- 40 rod 3. All the connecting-rods engage with the cranks of a crankshaft 4, and the cranks are set at any desired angles to each other. 45 In the engine shown the two outer cranks are arranged at one side of the crankshaft and the two inner cranks at its opposite side, this being a good arrangement for distributing the strains on the crankshaft. The 50 cranks may however be arranged at equal or unequal distances around the crankshaft in spiral order.

The admission and exhaust of all four cylinders are effected by a single rotary valve 55 working in a valve casing 6 arranged at the other ends of the cylinders from the

crankshaft. This rotary valve is provided with a valve spindle 7, and is driven from the crankshaft by any suitable driving mechanism, such as a drive chain 8 and sprocket wheels 9. The engine is of the four cycle type, and the valve is revolved once to each two revolutions of the crankshaft. The crankshaft is mounted in suitable bearings, and it and the driving mechanism are inclosed in any suitable casing or casings. The valve spindle 7 is shown as being formed integral with the valve, and it extends longitudinally through it and forms a central hub. Ball bearings 10, or other anti-friction bearings, are preferably provided at the end portions of the valve, between it and its casing; and the valve is provided with rings and strips, or other approved packing devices, at various points. 70 These packing devices are omitted in the drawings, for the sake of clearness, as they do not differ from those commonly used on rotary valves. The valve has a circumferential exhaust groove 14 at each end portion adjacent to its ball bearings, and it also has a circumferential exhaust groove 15 at its middle part. The exhaust groove 15 preferably has bridge-pieces 16 extending across it at the periphery of the valve, to 85 strengthen the valve at this point, and the exhaust grooves 14 may also be provided with bridge-pieces if desired.

A single exhaust pipe 17 is provided and is connected to the exhaust grooves by means 90 of a suitable port or ports 18 in the valve casing. When the exhaust pipe 17 is connected to the exhaust grooves by a plurality of ports, each exhaust groove has a similar exhaust port arranged opposite to it, and 95 the exhaust ports are connected to the exhaust pipe 17 by a manifold 19.

A single admission pipe 20 for the inflammable charge is provided, and has a forked end portion 21 which communicates 100 with two similar inlet ports 22. These inlet ports are arranged in the side of the valve casing opposite two inlet notches or grooves 24 and 25 formed in the valve. The inlet notches or grooves are arranged in the valve 105 midway between the middle exhaust groove 15 and the two end exhaust grooves, and each inlet notch or groove extends partway around the periphery of the valve.

The two inner power cylinders are designated by the numerals 30 and 40, and the two outer cylinders by the numerals 50 and

60. These cylinders have ports 31, 41, 51, and 61, respectively, at their ends, which ports communicate with the valve casing. These ports are arranged in line with each other and each port is of about the same length as the diameter of the cylinder to which it pertains, and is comparatively narrow. The two inner cylinders 30 and 40 are supplied with their combustible charges by means of cavities 32 and 42 respectively, in the valve. These inlet cavities 32 and 42 are arranged at different points of the periphery of the valve, and they have no direct communication with each other. The cavity 32 communicates with the inlet notch or groove 24 in the valve by means of a port 33; and the cavity 42 communicates with the inlet notch or groove 25 by means of a port 43, which is reversely similar to the port 33.

5 The cavities 32 and 42 are arranged in the valve so that they work opposite the ports 31 and 41 respectively. The valve has also four exhaust cavities 34, 44, 54, and 64, arranged at different points of its periphery and so that they work opposite the ports 31, 41, 51, and 61, respectively. These exhaust cavities are all connected together. The adjacent ends of the exhaust cavities 34 and 44, at the middle part of the valve, are connected to the circumferential exhaust groove 15 by ports 35 and 45 respectively, and are thereby also placed in communication with each other. The adjacent ends of the exhaust cavities 34 and 54 are connected together by a port 55 formed spirally in the solid side portion of the valve opposite the inlet notch or groove 24. The other end of the exhaust cavity 54 is open to the exhaust groove 14 at one end portion of the valve.

10 The adjacent ends of the exhaust cavities 44 and 64 are connected together by a port 65 formed spirally in the solid side portion of the valve opposite the inlet notch or groove 25. The other end of the exhaust cavity 64 is open to the exhaust groove 14 at the corresponding end portion of the valve. The valve has also two inlet cavities 52 and 62 arranged at different points of its periphery and so that they work opposite the cylinder ports 51 and 61 respectively. The inlet cavity 52 communicates with the inlet notch or groove 24 by means of a port 53, and is therefore able to receive its charge through it from the inlet pipe. The inlet cavity 62 communicates with the inlet notch or groove 25 by means of a port 63, and is also supplied with combustible gas from the inlet pipe 20.

15 The inlet notches or grooves 24 and 25 each extend around the periphery of the valve for more than the peripheral extension of the two inlet cavities pertaining to them, so that a free supply of inflammable fluid is provided for each cylinder.

20 The valve is revolved in the direction of

the arrow in Fig. 3, and each cylinder is controlled by its own portion of the valve. The valve is shown in Fig. 3 with its exhaust cavity opened to the cylinder port. The periods of exhaust, suction, compression, and power, are indicated on this Fig. 3 by means of dotted curved lines having arrow heads at their ends and marked E, S, C, and P, respectively. These periods may be relatively varied in extent in carrying out this invention, and are adjusted to give the best working results.

25 The inflammable charge is distributed to the cylinders one after another by the valve, and when the valve is in the position shown in Fig. 2, the cylinders 60, 40, 30, and 50, are respectively engaged in suction, compression, exhaust, and power. When the valve is revolved so that the exhaust of cylinder 30 is complete and its suction has commenced, the cylinders 60, 50, and 40 are respectively engaged in compression, exhaust, and power. All the cylinders are arranged to work in succession in this manner.

30 The cylinders and the valve have any suitable water-jackets or other means for cooling them.

35 This construction of valve besides being very simple, permits of very long periods of full port opening during inlet and exhaust periods; the distribution of the combustible charge is positive at all motor speeds; an ample exhaust is provided; the temperature is substantially the same at different points of the length of the valve; all parts are easy 40 of access; and the valve is driven and operated without noise or vibration.

45 What I claim is:

1. The combination, with a plurality of power cylinders arranged to work successively and provided with an exhaust pipe, of a single rotary valve provided with a central hub and having a circumferential exhaust groove which encircles the said hub and communicates constantly with the said exhaust pipe, said valve having also a separate exhaust cavity for each cylinder and having lateral ports, in the end walls of the exhaust cavities around the said hub, which place the exhaust cavities in constant communication with each other and with the said circumferential exhaust groove.

50 2. The combination, with a plurality of power cylinders arranged to work successively and provided with an exhaust manifold pipe, of a single rotary valve provided with a central hub and having a series of circumferential exhaust grooves which encircle the said hub and communicate constantly with the said manifold pipe, said valve having also a separate exhaust cavity for each cylinder and having lateral ports, in the end walls of the exhaust cavities around the said hub, which place the exhaust cavities in constant communication

with each other and with the series of circumferential exhaust grooves.

3. The combination, with a plurality of power cylinders arranged to work successively, of a single rotary valve provided with a central hub and having a separate pair of inlet and exhaust cavities for each cylinder, said valve having also a peripheral inlet notch or groove arranged around the 10 said hub between two of the pairs of cavities, and having also lateral ports, in the end walls of the inlet cavities around the said hub, which constantly connect the peripheral inlet notch or groove with the inlet 15 cavities on each side of it.

4. The combination, with a plurality of power cylinders arranged to work successively, of a single rotary valve provided with a central hub and having a separate 20 pair of inlet and exhaust cavities for each cylinder, said valve having also a peripheral inlet notch or groove partially encircling the said hub and an exhaust port formed in the partition wall of the exhaust cavities 25 around the said hub, said notch and port being arranged between two of the pairs of cavities and connecting the similar cavities together.

5. The combination, with a plurality of power cylinders arranged to work successively, of a single rotary valve provided with a central hub and having a separate 20 pair of inlet and exhaust cavities for each

cylinder, said valve having also a peripheral inlet notch or groove in it arranged around the said hub between two of the pairs of cavities and constantly communicating with the inlet cavity of each pair, said valve having also a port formed in its solid portion around the said hub and opposite the said 35 inlet notch or groove and constantly connecting the exhaust cavities of each pair.

6. The combination, with a plurality of power cylinders arranged to work successively, of a single rotary valve provided with a central hub and having a separate pair of inlet and exhaust cavities for each cylinder, said valve having circumferential exhaust grooves at its middle and end portions and longitudinal exhaust ports, in the end walls of its exhaust cavities around the said hub, which connect the exhaust cavities of each pair together and with the said exhaust grooves, said valve having also a peripheral inlet notch or groove in it arranged 50 around the said hub intermediate of each end exhaust groove and the middle exhaust groove and connecting together the inlet cavities of two adjacent pairs of cavities. 55

In testimony whereof I have affixed my 60 signature in the presence of two witnesses.
